W. K. BUCKLES,
FOUNTAIN PEN,
APPLICATION FILED DEC. 24, 1915.

Patented May 2, 1916.

Fig. 1

UNITED STATES PATENT OFFICE.

WILLIAM K. BUCKLES, OF RIFLE, COLORADO.

FOUNTAIN-PEN.

1,181,430.

Specification of Letters Patent.

Patented May 2, 1916.

Application filed December 24, 1915. Serial No. 62,584.

To all whom it may concern:

Be it known that I, WILLIAM K. BUCKLES, a citizen of the United States, residing at Rifle, in the county of Garfield and State of Colorado, have invented certain new and useful Improvements in Fountain-Pens, of which the following is a specification, reference being had to the accompanying drawings.

10 This invention relates to certain improvements in fountain pens and has relation more particularly to that type which are designed to contain within themselves means for filling the same and it is an object of the invention to provide a pen having novel and improved means wherein the reservoir may be readily and effectively compressed in order that a vacuum may be created so that when the wall of the reservoir assumes its 20 normal position, ink will be drawn in through the open end of the reservoir.

The invention consists in the details of construction and in the combination and arrangement of the several parts of my improved fountain pen whereby certain important advantages are attained and the device is rendered simpler, less expensive and otherwise more convenient and advantageous for use, all as will be hereinafter more 30 fully set forth.

The novel features of the invention will be carefully defined in the appended claims.

In order that my invention may be the better understood, I will now proceed to describe the same with reference to the accompanying drawing, wherein—

Figure 1 is a view, partly in elevation and partly in section, illustrating a fountain pen constructed in accordance with an embodiment of my invention; Fig. 2 is a longitudinal sectional view of my improved pen, the line of section being substantially at right angles to that illustrated in Fig. 1; Fig. 3 is a transverse sectional view taken through the barrel, detached, with the inner face of the closed end or head of the barrel in elevation; Fig. 4 is a sectional view taken substantially on the line 4—4 of Fig. 1; Fig. 5 is a view in top plan of a pen illustrating a further embodiment of my invention; and Fig. 6 is a sectional view taken substantially on the line 6—6 of Fig. 5, with parts omitted.

As disclosed in the accompanying drawing, 55 1 denotes the barrel of my improved fountain pen which supports or carries in

any desired manner the usual pen stock or nozzle 2 which in turn is provided with a passage 3 for the writing fluid. The passage 3 communicates with the pen 4 and the feeder bar 5 in the usual way and the upper or inner end of the stock or nozzle 2 is provided with a reduced portion or neck 6 to which the compressible reservoir 7 is connected, said reservoir being preferably 65 formed of rubber.

As herein embodied, the lower or open end of the reservoir is stretched over the reduced portion or neck, thereby holding itself in applied position by the elasticity of the rubber. To further assure the connection between the reduced portion or neck 6 and the reservoir 7, I find it of advantage to employ the split metallic ring or band 8 possessing sufficient inherent resiliency as to serve 75 to assure an effective connection between the reservoir 7 and the reduced portion or neck 6.

In order to fill the reservoir 7, I provide an improved means adapted to collapse or 80 flatten the reservoir whereby a partial vacuum is caused and when the reservoir is allowed to expand, the pressure of the outside atmosphere will force the ink within the reservoir. As herein disclosed my improved means comprises an elongated plate or shoe 9 which is substantially flat and co-extensive with the reservoir throughout the length thereof and the lower or inner end of the plate or shoe 9 is provided adjacent 85 one longitudinal margin with the extension or pintle 10 adapted to be inserted within an opening 11 produced in the split ring or band 8 whereby said band or ring serves as a bearing or mounting for the inner end of 90 the plate or shoe 9 so that the same may have a rocking movement. The opposite end of the corresponding longitudinal margin of the plate or shoe 9 is provided with an extension or pintle 12 adapted to be seated 95 within a recess or cavity 14 formed in the under face of the cap or head 15 at the upper or outer end of the barrel.

The head of the barrel 15 is provided with an arcuate slot 16 through which extends 100 the finger or extension 17 extending outwardly from the upper end of the free longitudinal margin of the plate or shoe 9 and as herein disclosed said lug or extension is preferably a continuation of a metallic 105 strand of requisite gage coextensive with the length of the shoe or plate 9 and se-

cured thereto throughout the length of the shoe or plate. It will be readily perceived that the finger or extension 17 may be readily engaged by a digit of the hand of the user and operated in such a manner as to collapse the reservoir 7 to create the requisite vacuum therein for a purpose which has hereinbefore been fully set forth.

In order to maintain the plate or shoe 9 against accidental rocking movement which would result in a collapsing of the reservoir 7, I employ, as illustrated in Figs. 5 and 6, the flat spring 18 pivotally engaged as at 19 to the outer face of the barrel 15^a which extends across the slot 16^a and engages the finger or extension 17^a, said spring 18 being normally positioned within the elongated recess 20 formed in the outer face of the head 15^a whereby, as is particularly illustrated in Fig. 5, it will be noted that the shoe or plate is effectively held against rocking movement. When it is desired to compress the reservoir 7 it is only necessary to elevate the spring 18 from within the recess 20. It will also be understood that if desired, a cap may be engaged with the closed end of the barrel 1, although this itself forms no part of my present invention.

From the foregoing description, it is thought to be obvious that a fountain pen constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

1. In a self-filling fountain pen, the combination with a barrel having one end closed, a stock coacting with the open end 50 of the barrel, a collapsible reservoir within the barrel and engaged with the stock, a clamping member embracing the reservoir and the stock, said clamping member and the closed end of the barrel being provided 55 with recesses, an elongated plate associated with the reservoir, the opposite ends of a longitudinal margin of the plate being provided with extensions seated within the recesses of the closed end of the barrel and 60 the clamping member whereby said plate is mounted for rocking movement, said plate being provided with means extending exteriorly of the closed end of the barrel for

imparting rocking movement to the plate to collapse the reservoir. 65

2. In a self-filling fountain pen, the combination with a barrel and a collapsible reservoir therein, a plate associated with the reservoir and mounted for rocking movement, said plate being provided with a finger extending exteriorly of the barrel and affording an operating means for the plate, and a spring member carried exteriorly of the barrel and coacting with the finger for holding the plate against rocking movement. 70

3. In a self-filling fountain pen, the combination with a barrel and a collapsible reservoir therein, a plate associated with the reservoir and mounted for rocking movement, said plate being provided with a finger extending exteriorly of the barrel and affording an operating means for the plate, and a spring member carried exteriorly of the barrel and coacting with the finger for holding the plate against rocking movement, the adjacent face of the barrel being provided with a recess in which the spring member is normally seated. 80

4. In a self-filling fountain pen, the combination with a barrel and a collapsible reservoir therein, a plate associated with the reservoir and mounted for rocking movement, said barrel being provided with a slot in its closed end, said plate being provided with 90 a finger extending exteriorly of the barrel through the slot in the closed end of the barrel and affording an operating means for the plate, and a spring member carried by the outer face of the closed end of the barrel 100 and overlying the slot for holding the plate against rocking movement.

5. In a self-filling fountain pen, the combination with a barrel and a collapsible reservoir therein, a plate associated with the reservoir and mounted for rocking movement, said barrel being provided with a slot in its closed end, said plate being provided with a finger extending exteriorly of the barrel through the slot in the closed end of 110 the barrel and affording an operating means for the plate, and a spring member carried by the outer face of the closed end of the barrel and overlying the slot for holding the plate against rocking movement, the outer 115 face of the barrel being provided with an elongated recess in which the spring member is normally seated, said recess serving to prevent accidental displacement of the spring. 120

In testimony whereof I hereunto affix my signature in the presence of two witnesses.

WILLIAM K. BUCKLES.
